UNITED STATES PATENT OFFICE.

HENRY LEITNER, OF LONDON, ENGLAND.

MEANS FOR REGULATING ELECTRIC-LAMP CIRCUITS.

1,100,584.

Specification of Letters Patent. Patented June 16, 1914.

Application filed April 11, 1912. Serial No. 690,053.

To all whom it may concern:

Be it known that I, HENRY LEITNER, a subject of the King of Great Britain, residing at 7 Prince's street, Westminster, London, England, have invented new and useful Improvements in Means for Regulating Electric-Lamp Circuits, of which the following is a specification.

The invention relates to electric regulators and the like, chiefly of the automatic type, such as are described in the specification of my British Patents Nos. 21,145 and 25,784 of 1904 and 6,690 of 1906, applied to lamp or other circuits of the kind wherein a dynamo is arranged in conjunction with a battery of accumulators, and is specially applicable to a mixed system of electric lighting, such as is commonly used for train lighting and the like, wherein both the battery and the dynamo provide current for the electric lamps fed by the system. Such a regulator as described in the said specifications consists of a rheostat designed to introduce resistance into the lighting or other circuit (which I will hereafter refer to in general as the lamp circuit) in order to compensate for variations in the voltage of the battery so that the voltage across the lamps is maintained approximately constant. The rheostat resistances are introduced into, and withdrawn from, the lamp circuit by means of a rheostat arm which is moved over resistance contacts by an electro-motor controlled by a voltmeter-control or balance in parallel with the lamps.

The voltmeter-control is provided with two electric contacts which are so arranged in the circuit of the electro-motor that when one of them is connected the motor will work in one direction of rotation, and when the other is connected the motor will work in the other direction, and the rheostat arm will have a corresponding motion in one direction or the other. The voltmeter control is so arranged as to have a neutral position in which neither contact is connected, and the motor is therefore inoperative, and the voltmeter-control, occupying electrically the position of a lamp in the lamp circuit, will maintain this neutral position so long as the voltage of the lamp circuit is maintained at its normal value. Should this voltage, however, rise above the normal the voltmeter-control will respond and the motor and rheostat arm will be operated so as to insert resistance in series with the lamp circuit. If

now the voltage again falls, resistance will be cut out. That end of the rheostat at which the position of the traveling arm will be such that the whole of the resistance is inserted in the lamp circuit, I term the "high" end of the regulator, and that end at which all the resistance is cut out, I term the "low" end.

My present invention relates to some additions and improvements in this regulator, and it provides that when the lamps are switched off the traveling arm shall under normal conditions travel up to the "high" end, and therefore, when the lamps are next switched on, the whole of the rheostat resistance will be in circuit and there will be no possibility of the lamps being over-volted if by any reason the voltage of the dynamo and batteries is above the normal.

My invention further provides that the regulator may act as a battery over-discharge preventer, and for this purpose, I provide certain devices at the "low" end of the regulator, as hereinafter described.

To enable my invention to be fully understood, I will describe it by reference to the accompanying drawings in which:

Figure 1 is a diagrammatic view of a lamp circuit supplied from a dynamo and accumulators, and provided with regulating means according to my invention. Figs. 2 and 3 are similar views embodying some modifications, and Figs. 4 and 5 are an elevation and a longitudinal section respectively of a detail drawn to a larger scale.

In these drawings, in which the same letters refer to the same or corresponding parts in all the figures, the regulator is shown in a straight bar form, but the contrivances described and illustrated are equally applicable to a circular form of regulator.

Referring first to Fig. 1, *a* represents the dynamo, *b* the accumulators and *c* a bank of lamps. *d* is the rheostat resistance, and *e* is the movable rheostat arm. *f* is the voltmeter-control and *g* the electro-motor controlled by the voltmeter and mechanically connected to the rheostat arm *e* by means of gearing. In this instance I have shown the arm *e* mounted on a rack bar *e¹* driven by a pinion *e²* which is connected by a belt or chain *e³* with the armature of the motor *g*, as indicated in the drawing. The rotation of the motor *g* in either direction and the consequent travel in one di-

rection or the other of the rheostat arm *e* is effected by the contacts *n*, *n*¹ of the voltmeter-control *f*. *h*, *h*¹ are trigger-switches which break the motor circuit when operated by the arm *e* at the farther end of its travel along the rheostat in either direction, and thus automatically stop the further motion of the arm and at the same time preserve the motor from damage and wasteful current. These switches are normally held closed by springs *h*². *l* is another trigger switch also normally held closed by a spring *l*², of similar construction to the switches *h*, *h*¹, which breaks the voltmeter circuit and consequently causes the breaking of the motor circuit at the "high" end of the rheostat, that is to say, at that end at which all the rheostat resistance has been inserted in the lamp circuit. The switch *l* is operated by the arm *e* preferably a little before the arm operates the switch *h*¹.

i is the main lamp switch having the contact *k* for the lamp circuit, and the auxiliary contacts *m*, *m*¹, which are in parallel with the contacts of the trigger-switch *l*, and which short-circuits them, and, therefore, restores the voltmeter circuit when the lamp switch *i* is closed.

At the "low" end of the rheostat (*i. e.*, at that end at which all the rheostat resistance has been cut out of the lamp circuit) the voltmeter circuit may also be broken by suitable means here shown as a gap *o* in the contact-rail *p* of the rheostat. A similar gap *g* in the contact-rail *r* which feeds the lamp circuit serves to break this latter circuit when the arm *e* passes beyond it on the "low" side, or this break may also be effected by means of a switch operated by the arm *e*.

s is the retrogressive resistance or resistances which is or are normally in circuit with the voltmeter when the latter is energized through the arm *e* and the slide-rail *u*, but which is or are cut out of circuit as the arm *e* passes over in the "low" direction. When, however, the arm reaches the slide-rail *u*¹, this resistance or these resistances is or are again inserted. An additional resistance *t* may also in some cases be introduced.

v is a contact connected with the release wire of an electro-magnetic distance switch operating in the lamp circuit, and in Fig. 1 is merely additional or supplementary to the break *q* in the lamp circuit on the slide-rail *r* already mentioned.

w is an auxiliary wire which is connected at one end with the extreme end *p*¹ of the slide-rail *p*, and at the other end with a contact *x* on the automatic cut-in and cut-out dynamo switch *y*.

z is a hand-switch or push which may also be employed to connect the auxiliary wire *w* with the battery *b*. The auxiliary

wire *w* may be extended to other regulators so as to operate them simultaneously.

The operation of the apparatus is as follows:—When the lamp switch *i* is put in the "off" position, the diminished load will cause the voltage of the circuit to rise, and the voltmeter-control *f* will be actuated so as to make a contact for the motor *g* on the "high" side, namely at the contact *n*. The arm *e* will then travel up the scale, and on reaching the switch *l* this will be opened and the voltmeter-control circuit broken. The switch *h*¹ may or may not be operated by the arm *e* after the switch *l* is operated. The switch *h*¹ is provided as a precautionary measure, as the arm *e* travels a short distance after the motor circuit has been broken, which may be sufficient in some instances to bring it into contact with the arm of the switch *h*¹ and for the reason that if the voltage of the supply circuit should rise abnormally when the switch *i* is closed, the switch *l* would be short-circuited and the arm *e* would then tend to move to the right and would engage and operate the switch *h*¹ and break the motor circuit, which otherwise would not be broken under those circumstances. If now the lamps are again switched on by the main lamp switch *i*, the contacts *m*, *m*¹ will also be closed, and thereby the break in the voltmeter-control circuit, caused by the opening of the switch *l*, will be short-circuited, and the voltmeter-control *f* will operate in conjunction with the motor *g*, to accommodate the arm *e* on the resistance *d* to the normal voltage of the lamp circuit.

When the dynamo *a* is not in operation the lighting current will be taken wholly from the accumulators *b*, and as these latter are gradually discharged the voltage of the circuit will fall. The voltmeter-control *f*, however, is adjusted to a certain predetermined voltage, and if the lamp circuit falls below this standard voltage the voltmeter will "make" a circuit for the motor *g* at the contact *n*¹ and will cause the rheostat arm *e* to travel toward the "low" end, thereby cutting out resistance from the lamp circuit and raising the voltage of the same to the standard value. This action will go on until there is no longer any resistance left to cut out of the lamp circuit. As it may not be advisable, however, to break the lamp circuit until the voltage has fallen to a still lower value, I provide that at this point the resistance or resistances *s* in the voltmeter circuit shall now be cut out gradually, thus placing the calibration of the voltmeter-control on a lower scale. When all the resistance or resistances *s*, however, has or have been cut out, the voltmeter will "make" the contact *n*¹ and will be unable to recover itself by any further adjustment of resistances on the rheostat, with the consequence that the motor *g*

will continue to operate the arm e so as to cause it to travel to the extreme "low" end of the rheostat, where it will finally be brought to rest by the opening of the trigger-switch h and the consequent breaking of the motor circuit. The arm e will now be in the position shown by the dotted lines, and it will readily be seen that in this position the voltmeter circuit is broken at the gap o because the voltmeter derives its current from the slide-rail p through the arm e and the slide-rail u . The lamp circuit is also broken at the gap q in the slide-rail r .

The opening of the lamp circuit at the gap q in the slide-rail r , or by the operation of a magneto-electric switch through the contact v , will cause a rise in the voltage of the accumulators, and in order that this rise may not affect the voltmeter-control f so as to energize the motor on the "high" side and thus bring back the rheostat arm, it is necessary that a resistance should be inserted in the voltmeter-control circuit when, or immediately before, the lamp circuit is broken. This is readily effected by arranging the circuit as shown in Fig. 1, where it will be seen that when the arm e has cut out all the retrogressive resistance or resistances s , and has reached the bar u^1 , the resistance or resistances s are again inserted in the voltmeter circuit. The voltmeter circuit being now broken, and the lamp circuit being also broken at the gap q , independently of the main lamp switch i , which may have been inadvertently left in the "on" position, it is obvious that the rheostat arm e must be again brought forward, or made to travel some distance toward the "high" end of the rheostat before the normal working conditions are restored. One very simple way of doing this is to provide a push-button or its equivalent z , which can temporarily short-circuit the break o in the slide-rail p , and thus energize the voltmeter through the arm e and the slide-rail u^1 . If, under these conditions, the accumulators had in the meantime been recharged, so that their voltage was again normal, then the closing of the voltmeter circuit by means of the push z would cause the control balance f to make contact on the "high" side at n and would thus energize the motor g in the direction of rotation to cause the rheostat arm e to travel up the scale toward the "high" end. If the main lamp switch i were now in the "on" position the arm e would be adjusted by the voltmeter-control to the normal or standard voltage of the lamp circuit, but if the lamp switch i was in the "off" position, and the voltage of the accumulators was higher than that of the normal to which the voltmeter was adjusted or calibrated, then the arm e would continue to travel toward the "high" end of the rheostat, where the voltmeter circuit would be again broken by the switch l , and the motor

circuit by the switch h^1 . It is possible, however, that the accumulators may not have been recharged, but are still at their abnormally low discharge voltage, and it, therefore, becomes necessary to provide means whereby their further discharge is rendered impossible by the restoration of the lamp circuit. 70

With the arrangement of apparatus already described this will be automatically insured in the following manner. If the voltage of the accumulators is no higher than that at which they were left when the rheostat arm had traveled to the extreme "low" end of the scale, the voltmeter-control 75 will be unable to respond when energized by the operation of the push z , and the arm e will consequently remain at the "low" end. But, if, as will generally be the case, there has been a rise in the voltage of the accumulators due to their open circuit, the operation of the push z will cause a movement of the arm e for a certain distance, but only a temporary and partial movement, since so soon as current is again taken by the lamps 80 the voltage will quickly fall, and the arm e return to the "low" position. It is, therefore, not merely undesirable, but with the apparatus here provided it is impossible, to restore the lamp circuit in the discharged 85 state of the accumulators. Instead, however, of restoring the rheostat arm e to its normal working position by means of a hand push or similar device, I may do so automatically as soon as the dynamo commences to work. This is accomplished in 90 the following manner. In connection with the usual automatic cut-in and cut-out device or switch y , which is placed between the dynamo and the accumulators, I provide 95 an additional contact x , and this contact serves to connect an auxiliary wire w with the main circuit of the battery. At the other end this auxiliary wire w is connected to the slide-rail p^1 at the "low" end of the 100 rheostat, and on which the arm e rests when in the "low" position. As soon, therefore, as the auxiliary wire w is energized through the contact x by the cutting in of the automatic switch y , a current can pass through 105 the auxiliary wire w , through the arm e and the slide-rail u^1 to the voltmeter, which, being now energized by the higher voltage of the dynamo, will make contact for the motor 110 on the "high" side at n , and will thus bring the rheostat arm back to its normal position. 115

In any system in which the parallel working of two or more dynamos and sets of accumulators is employed, or in which two or more lamp circuits, each controlled by its own regulator, are linked in parallel circuit, as is shown for example in the specification of British Patent No. 27,396 of 1910, an extension of the auxiliary wire w may be taken to the additional regulator or regula- 120

tors, so that all may be re-established together, for in such a case each set of accumulators will have been discharged to the same extent, and the rheostat arm on every 5 regulator will drop to the "low" position, while each and all must be kept out of action or brought into action together.

It is generally advisable that on the "down" motion of the rheostat arm the 10 lamp circuit should be broken after the voltmeter circuit, while on the "upward" motion taking place the voltmeter circuit and the contact of the arm *e* with the slide-rail *p* should be established before the lamp circuit 15 is established on the slide-rail *r*. This will prevent any possibility of a lamp current passing through the auxiliary wire *w* or the push *z* and through the arm *e* to the slide-rail *r* when the arm *e* moves forward, and 20 before the gaps *o* and *q* have been entirely passed.

In order to insure that the lamp circuit on the slide-rail *r* may thus be broken last and also established last, I provide that the 25 arm *e* shall be furnished at that portion which passes on the slide-rail *r* with a contact piece having a small amount of play or drag in the direction of the motion of the arm. This is shown in Figs. 4 and 5 30 where *c*¹, *c*², *c*³ represent the contact-pieces in the underside of the arm, the contact *c*² bearing upon the slide-rail *r* and being allowed to have slight play transversely across the arm *e* in the direction of the 35 arrow Fig. 4. Thus in whichever direction the arm is moving the contact-piece *c*² will be slightly behind the center of the arm.

Figs. 2 and 3 illustrate modifications of the arrangement shown in Fig. 1 in which 40 the auxiliary wire *w* is dispensed with, and use is made of an electromagnetic release main lamp switch. In the arrangement illustrated in Fig. 2 when the arm *e* travels down to the "low" end of the rheostat as previously described with reference to Fig. 1, it operates the switch *v*, thereby making a temporary contact for the release circuit of the electromagnetic switch *i*, of which *i*¹ is the release coil or solenoid, as is well understood. The 45 voltmeter circuit is broken at the gap *o* as previously described, and under these conditions the arm *e* will remain at the "low" end of the rheostat. In order to restore the arm *e* to its normal working position when 50 the lamps are switched on, I provide two auxiliary contacts *k*¹ and *k*² on the main lamp switch, which contacts are closed when the main switch is closed, and which then 55 form a short circuit across the gap *o* where the voltmeter circuit is broken.

With this construction, and if the accumulators have meanwhile been recharged so as to recover their normal voltage, the 60 arm *e* will move forward into its normal position, but if the accumulators are still

discharged the voltmeter-control will be unable to operate so as to effect this result, or will only operate for a very short time, and the arm *e*, if brought forward at all, will quickly fall back, and in doing so will again operate the release switch *v* and put the main lamp switch *i* in the "off" position. 70

In the modification shown in Fig. 3 it is not intended that the arm *e* shall remain at the "low" end of the rheostat, but that in 75 every case it shall be brought up to the "high" end, and the voltmeter circuit broken there by means of the switch *l*. This is provided for in the following manner. *i* is, as in Fig. 2, an electro-magnetic release switch which is operated through the contact or switch *v* when the arm *e* reaches the "low" end of the rheostat. *k*¹, *k*² are the auxiliary contacts which are closed when the switch *i* is in the "off" position, and 80 these contacts serve to short-circuit the retrogressive resistance or resistances *s*. The slight recovery of voltage of the accumulator due to the open lamp circuit will now be sufficient, with the resistance or resistances *s* cut out of the voltmeter circuit, to energize the voltmeter on the "high" side and complete the motor circuit at *n*, whereby the arm *e* will commence to travel up the rheostat toward the "high" end, where it will 85 finally break the voltmeter circuit at the switch *l*, and the motor circuit at the switch *k*¹. In this arrangement, as in those shown in Figs. 1 and 2, the voltmeter circuit, when broken by the switch *l*, is restored when the 90 lamps are switched on, by means of the auxiliary contacts *m*, *m*¹ which are in parallel with the switch *l*, and which therefore short circuit the break when closed by the switch *i*. 95

Having now particularly described and 100 ascertained the nature of my said invention and in what manner the same is to be performed, I declare that what I claim is:—

1. In an electric system, the combination with a lamp circuit, a battery of accumulators, a dynamo, a rheostat having a movable arm, a series of resistances in the lamp circuit adapted to be cut in and out by said arm, a motor for operating said arm, a voltmeter control device for said motor, of automatically operable means for breaking and 110 restoring both the lamp circuit and the voltmeter control circuit. 110

2. In an electric system, the combination with a lamp circuit, a battery of accumulators, a dynamo, a rheostat having a movable arm, a series of resistances in the lamp circuit adapted to be cut in and out by said arm, a motor for operating said arm, a voltmeter control device for said motor, of 115 means operatively controlled by the rheostat arm for breaking and restoring the voltmeter control circuit when the rheostat arm has been moved into position to cut in substantially all the said series of resistances. 120

3. In an electric system, the combination with a lamp circuit, a battery of accumulators, a dynamo, a rheostat having a movable arm, a series of resistances in the lamp circuit adapted to be cut in and out by said arm, a motor for operating said arm, a voltmeter control device for said motor, of a normally closed switch in series with the voltmeter control and having a part adapted to be operated by the rheostat arm after it has cut out all resistance from the lamp circuit, to open said switch.

4. In an electric system, the combination with a lamp circuit, a battery of accumulators, a dynamo, a rheostat having a movable arm, a series of resistances in the lamp circuit adapted to be cut in and out by said arm, a motor for operating said arm, a voltmeter control device for said motor, of a normally closed switch in series with the voltmeter control and having a part adapted to be operated by the rheostat arm after it has cut out all resistance from the lamp circuit, contacts in parallel with said switch for short-circuiting the same, and a lamp circuit switch adapted to connect said contacts when in closed position.

5. In an electric system, the combination with a lamp circuit, a battery of accumulators, a dynamo, a rheostat having a movable arm, a series of resistances in the lamp circuit adapted to be cut in and out by said arm, a motor for operating said arm, a voltmeter control device for said motor, of a means operatively controlled by the rheostat arm for breaking and restoring both the lamp circuit and the voltmeter control circuit when the rheostat arm is in position to cut out substantially all of said series of resistances.

6. In an electric system, the combination with a lamp circuit, a battery of accumulators, a dynamo, a rheostat having a movable arm, a series of resistances in the lamp circuit adapted to be cut in and out by said arm, a motor for operating said arm, a voltmeter control device for said motor, of a resistance in series with the voltmeter control, adapted to be cut out of circuit as the rheostat arm travels toward the end of the rheostat at which said series of resistances are cut out, to change the calibration of the voltmeter control.

7. In an electric system, the combination with a lamp circuit, a battery of accumulators, a dynamo, a rheostat having a movable arm, a series of resistances in the lamp circuit adapted to be cut in and out by said arm, a motor for operating said arm, a voltmeter control device for said motor, of an auxiliary resistance in series with the voltmeter control, means for cutting out said resistance when the rheostat arm has traveled a certain distance toward the end of the rheostat at which said series of resistances

are cut out, and means for thereafter cutting in said auxiliary resistance into the voltmeter control circuit by the further travel of the rheostat arm.

8. In an electric system, the combination with a lamp circuit, a battery of accumulators, a dynamo, a rheostat having a movable arm, a series of resistances in the lamp circuit adapted to be cut in and out by said arm, a motor for operating said arm, a voltmeter control device for said motor, of a resistance in the voltmeter control circuit for changing the calibration of the voltmeter control, means operable by the rheostat arm for cutting out said calibrated resistance, and a normally closed switch in series with the voltmeter control having a part adapted to be operated by the rheostat arm for breaking the voltmeter control circuit after the resistance has been cut out of the lamp circuit, and said calibrating resistance has been cut out.

9. In an electric system, the combination with a lamp circuit, a battery of accumulators, a dynamo, a rheostat having a movable arm, a series of resistances in the lamp circuit adapted to be cut in and out by said arm, a motor for operating said arm, a voltmeter control device for said motor, of a normally closed switch in the lamp circuit and having a part adapted to be operated by the rheostat arm for breaking the lamp circuit when the voltage has fallen to a predetermined limit.

10. In an electric system, the combination with a lamp circuit, a battery of accumulators, a dynamo, a rheostat having a movable arm, a series of resistances in the lamp circuit adapted to be cut in and out by said arm, a motor for operating said arm, a voltmeter control device for said motor, of a normally closed switch in series with the voltmeter control having a part adapted to be operated by the rheostat arm for opening said switch after the rheostat arm has cut out all the resistance from the lamp circuit, and auxiliary means for restoring the voltmeter control circuit when so broken, independent of said switch.

11. In an electric system, the combination with a lamp circuit, a battery of accumulators, a dynamo, a rheostat having a movable arm, a series of resistances in the lamp circuit adapted to be cut in and out by said arm, a motor for operating said arm, a voltmeter control device for said motor, of a normally closed switch in series with the voltmeter control having a part adapted to be operated by the rheostat arm for opening said switch after the rheostat arm has cut out all resistance from the lamp circuit, and auxiliary means for restoring the voltmeter control circuit, independent of said switch.

12. In an electric system, the combina-

tion with a lamp circuit, a battery of accumulators, a dynamo, a rheostat having a movable arm, a series of resistances in the lamp circuit adapted to be cut in and out by said arm, a motor for operating said arm, a voltmeter control device for said motor, of an electro-magnetic switch in the lamp circuit, a circuit therefor, and a switch in said circuit for controlling the electro-magnetic switch and having a part adapted to be operated by the rheostat arm, whereby the electro-magnetic switch is energized and the lamp circuit broken, when the voltage of the lamp circuit has fallen to a predetermined limit.

13. In an electric system, the combination with a lamp circuit, a battery of accumulators, a dynamo, a rheostat having a movable arm, a series of resistances in the lamp circuit adapted to be cut in and out by said arm, a motor for operating said arm, a voltmeter control device for said motor, of a normally closed switch for breaking the voltmeter control circuit located adjacent to the end of the rheostat at which all of said series of resistances are cut in and having a part adapted to be operated by the rheostat arm, an electro-magnetic switch in the lamp circuit, a circuit therefor, a switch for controlling said circuit having a part adapted

to be operated by the rheostat, auxiliary contacts in operative relation with the electro-magnetic switch, a circuit for said contacts, for short-circuiting the switch in the voltmeter control circuit, and means operated by the electro-magnetic switch for closing the circuit through said contacts. 35

14. In an electric system, the combination with a lamp circuit, a battery of accumulators, a dynamo, a rheostat having a movable arm, a series of resistances in the lamp circuit adapted to be cut in and out by said arm, a motor for operating said arm, a voltmeter control device for said motor, of a plurality of contacts adapted to be engaged by the rheostat arm, a fixed contact portion on the rheostat arm for engaging one or more of said contacts, a self-adjusting contact movably connected to the rheostat arm and provided with a limited amount of lost motion with respect thereto, whereby when the rheostat arm reverses its direction of movement, the said self-adjusting contact will change its position with respect to the fixed contact portions of the rheostat arm. 40 45 50 55
